(57) **CLAIM**

The ornamental design for a human body detector as shown and described.

DESCRIPTION

FIG. 1 is a front, right and top perspective view of a human body detector, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the human body detector in another state.

The broken lines shown in the drawings are included for the purpose of illustrating portions of the human body detector that form no part of the claimed design.

1 Claim, 9 Drawing Sheets
